UNITED STATES PATENT OFFICE.

GEORGE BROWN, OF BAYONNE, NEW JERSEY.

FILTERING-PRESS.

1,181,729.

Specification of Letters Patent. Patented May 2, 1916.

Application filed July 3, 1915. Serial No. 37,841.

To all whom it may concern:

Be it known that I, GEORGE BROWN, a citizen of the United States, and a resident of Bayonne, in the county of Hudson and State 5 of New Jersey, have invented a new and Improved Filtering-Press, of which the following is a full, clear, and exact description.

My invention relates to filtering presses, and has reference more particularly to a 10 press whereby wax can be separated from mineral oils.

The object of the invention is to provide a simple, strong, inexpensive, and efficient filtering press whereby wax can be separated 15 from oil continuously, and not periodically as is done now.

With the above and other objects in view, the nature of which will more fully appear as the description proceeds, the invention 20 consists in the novel construction, combination and arrangement of parts as herein fully described, illustrated and claimed.

In the accompanying drawings, forming part of the application, similar characters 25 of reference indicate corresponding parts in all the views.

Figure 1 is a plan view of an embodiment of my invention, a portion of which is broken out to show the details of construction; Fig. 2 is a longitudinal section on line 30 2-2, Fig. 1; Fig. 3 is a horizontal section on line 3-3, Fig. 2; Fig. 4 is a vertical cross section on line 4-4, Fig. 1; Fig. 5 is an enlarged plan view of a fragment of a drip 35 plate; and Fig. 6 is a fragmentary section of the head provided with removable breakers.

Referring to the drawings, 7 is the base of the press and 8 is the head secured to the 40 base at the margin by bolts 9. The head 8 is in the shape of a dome of elongated form and is narrower in width at the oil inlet 10 provided at the upper portion of the head. The width of the dome increases from the 45 inlet end 10 toward the middle of the dome where it continues substantially uniform in width, but the depth thereof slightly decreases; then it abruptly decreases in width to reach the outlet end 11 from the dome.

50 Positioned within the dome, between the inlet end and the wider portion thereof, are breakers 12, which can be movable or stationary, as shown in the drawings. It will be noted that every other breaker is spaced 55 from the top of the dome and has a rounded end thereat; while the lower end of each of

the second breakers is beveled, the inclination being directed toward the inlet. The purpose of this will appear hereinafter. By providing the breakers, the oil entering 60 through the inlet 10 is caused to circulate between the breakers, and thus crowding of the oil at the outlet 11 is prevented. Positioned on the base below the dome is a fabric 65 13 which is engaged and retained in position by the bolts connecting the dome to the base. Positioned below the fabric on the base is a perforated plate 14, which is preferably recessed in a dripping plate 15 forming an integral part of the base. The dripping plate comprises a plurality of perforations 15 interconnected at the surface where the perforated plate 14 is provided by grooves or channels 16 extending over the dripping plate. The base 7 is hollowed out 75 below the dripping plate to form a receptacle 17 having a beveled bottom to collect the liquid at one end of the base where an outlet 18 from the hollow part is provided. The base 7 has also an opening 19, preferably elbow shape, registering with the outlet 11 in the dome and forming a continuation of the outlet 11.

The oil from which the wax is to be separated is forced under pressure through the 80 inlet 10 into the dome. The oil pressed upon the fabric passes through the perforated plate on to the dripping plate, and from there it enters into the hollow 17 of the base and flows out through the outlet 18. The 85 wax particles which adhere to the fabric are gradually forced by the oil toward the outlet end 11 of the dome, whereat the base is provided with a smooth part 11' to facilitate the movement of the wax to the outlet 90 11 after leaving the fabric, and where-through the wax, and the oil that did not pass through the fabric, find their outlet and are delivered through the opening 19 to any suitable conduit 20, which conveys the wax 100 105 with the oil to a suitable receptacle, not shown in the drawings.

To facilitate the cleaning of the press without taking the same apart, a steam coil 21 is provided within the wide part of the 110 dome, and a steam passage 22 is provided within each of the breakers 12. Steam can be supplied to the coil and the passage 22 by conduits 23 and whereby the dome and the breakers can be heated; and by sending a suitable solvent through the inlet 10 the fabric and the dome will be thoroughly cleaned.

The breakers 12', in Fig. 6, are secured to the head by means of screws 24. This arrangement permits the removal of the breakers entirely and the utilization of the press 5 without the breakers when so desired.

From the above description it will be seen that by means of my process the separation of the wax from the oil can be made continuous, as the wax adhering to the fabric 10 13 is gradually removed therefrom by the oil forced into the press which finds its way to the outlet from the dome.

While I have described the principle of operation, together with the device which I 15 now consider to be the best embodiment thereof, I desire to have it understood that the device shown is merely illustrative and that such changes may be made as are within the scope of the appended claims.

20 I claim:

1. In a filtering press of the class described, an elongated dome having an inlet at one end and an outlet at the other end, breakers within the dome adjacent the inlet, 25 a base associated with the dome and spaced from the breakers, a filtering fabric carried by said base under the dome, and a perforated plate under said fabric, said base having a dripping plate below said perforated plate and wherethrough the liquid matter forced through the fabric can find an 30 escape, said base having an opening registering with the outlet of the dome.

2. In a filtering press of the class described, a dome, a base associated with the dome, a filtering fabric carried by the base under the dome, a perforated plate under said fabric, said dome having an inlet and an outlet, and means interposed between the inlet and outlet to offer resistance to the flow of fluid from the inlet to the outlet and maintain the fluid in contact with the filtering fabric, said base having means below the perforated plate to receive the liquid matter 45 forced through the fabric.

3. In a filtering press of the class described, an elongated dome having an inlet at one end and an outlet at the other end, a base associated with the dome, a filtering 50 fabric carried by said base under the dome, a perforated plate under said fabric through which the material passing through the fabric makes its escape, and means in the dome for breaking up the flow of liquid 55 from the inlet to the outlet whereby the liquid is caused to flow close to the filtering fabric.

4. In a filtering press of the class described, an elongated dome having an inlet 60 at one end and an outlet at the other end, breakers within the dome adjacent the inlet, a base associated with the dome and spaced from the breakers, a filtering fabric on said

base under the dome, said breakers adapted to break up the flow of liquid within the 65 dome from the inlet to the outlet and cause the liquid to flow in close proximity to the filtering fabric, a perforated plate under said fabric, said base being perforated below the perforated plate so as to form a 70 drip therefor, said base having a receptacle below the drip to receive the matter forced through the filtering fabric, and means for supplying heat to the dome and the breakers, substantially as and for the purpose set 75 forth.

5. In a filtering press of the class described, an elongated dome having an inlet at one end and an outlet at the other end, breakers within the dome adjacent the inlet 80 and disposed transversely of the longitudinal axis of the dome, a base associated with the dome and spaced from the breakers, a filtering fabric carried by said base under the dome, a perforated plate under said 85 fabric supported by the base, said base having a grooved surface under the perforated plate forming a dripping plate through which the material passing through the filtering fabric may escape, a receptacle 90 within the base below said dripping plate, and means for supplying heat to the breakers and to the dome near the outlet, substantially as and for the purpose set forth. 95

6. In a filtering press of the class described, an elongated dome, a base associated with the dome, a filtering fabric carried by the base under the dome, said dome having an inlet at one end thereof and an outlet 100 at the opposite end, said base having an outlet below the filtering fabric, said dome having means for restricting the free flow between the inlet and outlet thereof to maintain the fluid traveling from the inlet to the 105 outlet of the dome in contact with the filtering fabric.

7. In a filtering press of the class described, a casing having an inlet for fluid to be filtered and an outlet for the filtered 110 fluid, and a filtering fabric intercepting the flow from the said inlet to the said outlet, said casing having an additional outlet remote from said inlet and the flow to which is along the filtering fabric and not intercepted by said fabric, said casing having means for restricting the free flow along the filtering fabric from said inlet to said additional outlet. 115

In testimony whereof I have signed my 120 name to this specification in the presence of two subscribing witnesses.

GEORGE BROWN.
